Lonnie G. Baker, Loraine, Tex., assignor of fifty per cent to Roy Bridgewater, Sweetwater, Tex.

Application April 23, 1945, Serial No. 119,137

Term of patent 7 years

(Cl. D34—15)

To all whom it may concern:

Be it known that I, Lonnie G. Baker, a citizen of the United States, residing at Loraine, in the county of Mitchell and State of Texas, have invented a new, original, and ornamental Design for a Toy, of which the following is a specification, reference being had to the accompanying drawing, forming part thereof.

The figure is a perspective view of a toy, showing my new design.

I claim:

The ornamental design for a toy, as shown.

LONNIE G. BAKER.
